INTERLOCKING SYSTEM FOR RAILROADS

Sedgwick N. Wight, Rochester, N. Y., assignor to
General Railway Signal Company, Rochester,
N. Y.

Application July 18, 1936, Serial No. 91,322

30 Claims. (Cl. 246—134)

This invention relates to interlocking systems for railroads, and more particularly pertains to such an interlocking system in which a miniature track layout in a control office has located thereon the controlling buttons or levers for setting up the desired routes through the actual track layout and in which the electric circuit connections between such buttons or levers accomplish the control of all the various traffic controlling devices employed for the establishment of routes through the track layout.

The present invention relates to improvements in the interlocking systems disclosed in my prior applications Ser. No. 721,696, filed April 21, 1934 and Ser. No. 69,905 filed March 20, 1936.

The organization of the system embodying the present invention contemplates a miniature track layout located in the central control office which corresponds to the actual track layout in the field and has located thereon initiating and completing buttons for each of the route determining points on the track layout. In other words, for each signal location there is an initiating button, and for the end of each route there is a completion button. To establish a movement of traffic in a particular direction over a particular trackway route, it is necessary for the operator to actuate the initiating button at the entrance to such desired route and then actuate the completion button for the exit end of that route.

This contemporaneous operation of an initiating button and a completion button on the miniature track diagram provides for the transmission of route control codes over a multiple impulse code type communication system to the field location so as to compositely operate all of the track switches in such route to their proper positions after which the signal for that route clears to allow the passage of traffic over the route providing traffic conditions are safe for such passage.

It is also contemplated that this system will allow the control code for only one of several conflicting routes to be transmitted to the field location at any one time, so as to prevent any conflict of controls at the field location.

In accordance with the present invention, the preferred form of initiating or entrance button is of the knob type which may be turned to a particular position in which it remains; while the completion or exit button is of the self-restoring push button type. The system organization then renders a cleared route wholly dependent upon the manual restoration of only the

initiating or entrance button, the completion or exit button having been only momentarily in an operated position.

The entrance-exit method of control or manipulation so characterizes the system of the present invention, that it has been aptly termed entrance-exit interlocking or abbreviated as "NX Interlocking".

The system of the present invention also provides that under certain emergency conditions codes may be transmitted so as to individually operate the track switches in accordance with the positioning of their respective emergency switch control levers, one for each track switch. This individual emergency control of the track switches is accomplished without the clearing of any signal and is so organized as to be prevented if such switches are included within a cleared route.

Although the present invention is more particularly directed to the features of such an NX interlocking system employing code communication between the central office and the field location, it is to be understood that the various interlocking features involved in the control of complicated track layouts, such as shown in my application Ser. No. 69,905 filed March 20, 1936, are to be understood as applicable to the system of the present invention.

Other objects, purposes and characteristic features of the present invention will be in part obvious from the accompanying drawings, and in part pointed out as the description of the invention progresses.

In describing the invention in detail, reference will be made to the accompanying drawings, in which like reference characters designate the same parts throughout the several views; and in which like letters in the reference characters designate similar functions or relationships with the distinctiveness between such reference characters provided by the use of distinctive preceding numerals; in which like preceding numerals in the reference characters, when applied to different letters, represent the inclusion of such devices within a particular group; and in which:

Figs. 1, 2 and 3 when placed side by side illustrate the circuit arrangement employed in connection with the system of the present invention for setting up the route control codes for transmission over the multiple impulse type code communication system;

Fig. 4 illustrates certain parts of the code

transmitting apparatus employed in the central office;

Fig. 5 illustrates certain parts of the code receiving apparatus employed at the field location; and

Fig. 6 and 7 when placed side by side illustrate the decoding apparatus employed at the field location for controlling the individual traffic governing device in accordance with the route 10 control codes received.

Instead of showing the complete circuit arrangement by placing a large number of sheets side by side, a simplified method of disclosure has been employed wherein all of the control 15 circuits for any one relay are shown in a continuous relationship; while all of the circuits which that relay may control are distributed between the several sheets of drawings upon which that relay is shown in block form.

For the purpose of further simplifying the illustration and facilitating in the explanation thereof, the conventional parts and circuits constituting the embodiment of the invention have been shown diagrammatically and certain conventional 20 illustrations have been employed, the drawings having been made more with the idea of making clear the purpose and principles of the present invention together with its mode of operation than with the idea of illustrating the specific construction and arrangement of parts that 25 would probably be employed in practice.

The various relays and their contacts are illustrated in a conventional manner and symbols are employed to indicate connections to the terminals 30 of batteries or other suitable sources of electric current supply instead of showing all of the wiring connections to such terminals.

The symbols (+) and (−) are employed to indicate the positive and negative terminals respectively of suitable batteries or other sources of electric energy; and those terminals with which these symbols are used are presumed to have current flowing from the positive terminal designated (+) to the negative terminal designated (−).

The symbols employed with any one local circuit are considered to designate the terminals of the same battery or other suitable source, but as many separate sources may be provided as found necessary, or as many sources may be combined in 40 a single source as found necessary or expedient in the practice of the invention. If alternating current is employed, then these symbols should be considered to represent the instantaneous relative polarities of the respective terminals.

Where groups of devices are referred to in a general way, such devices will be designated by the letters or preceding numerals characteristic of such group instead of citing each specific reference character of that group.

Apparatus in general

Track layout—Fig. 7.—In the accompanying drawings, the invention has been shown applied 65 to a track layout including a stretch of double track connected by a cross-over TS. The stretch of double track includes a main line extending from a signal 1 to a signal 2, and another main line extending from the signal 4 to the 70 signal 6. Signals 3 and 5 govern traffic over the cross-over TS between the two main line tracks.

Inasmuch as the opposite ends of a cross-over are usually operated at the same time, the cross-over is considered as a single track switch TS and 75 is illustrated as operated by a single switch ma-

chine SM, which may be of any suitable type, such for example as disclosed in the patent to W. K. Howe, Patent No. 1,466,903, dated September 4, 1923. However, two switch machines may be employed having either individual or collective 5 control.

It should be understood that the invention is not limited, as thus shown, to the control of the cross-over and signals of this chosen track layout, but may be extended for any desired number of switches and signals and may be readily applied to all types of track layouts found in interlocking plants.

The signals 1, 2, 3, 4, 5 and 6 are assumed to be color light signals giving the usual indications of green for clear and red for danger or stop, and if an added indication is desired, yellow for caution. However, these signals may be of the search light type, semaphore type, or any other type of signal instead of the type chosen 20 for the embodiment of the present invention.

The track layout illustrated in Fig. 7 has been shown as divided into track circuit sections 14 and 15 by insulated joints indicated in the usual manner. These track sections are provided with the usual track batteries and track relays of which only the track relays 14T and 15T have been shown. These normally energized track circuits are wired in the usual manner to provide for fouling protection and to provide for the insulation of cross-overs and track switches, such details of wiring having been omitted for the sake of simplicity in the disclosure. These track circuits can of course be subdivided or lengthened as desired and arranged in accordance with any 30 of the usual practices.

The track switch TS is shown as having associated therewith a switch position repeating relay WP. This relay is of the polar-neutral type and is energized with one polarity or the other in accordance with the normal and reverse locked positions of the cross-over TS and switch machine SM, and is deenergized whenever the cross-over TS is unlocked or is in operation. The polarized circuit for controlling such a switch repeating relay is governed through the medium of a point detector contact mechanism as shown for example in the patent to C. S. Bushnell, Patent No. 1,517,236, filed November 25, 1924.

Control panel.—In the central office, a control machine includes a control panel on which is located a track diagram corresponding to the actual track layout in the field. This track diagram is shown as having a miniature cross-over 55 TS which is movable to normal or reverse positions by suitable electro-magnetic means in accordance with the position of a switch control relay Z. A similar miniature track switch has been shown in detail in my prior application Ser. No. 431,748, filed February 27, 1930.

On this control panel are entrance buttons NB 60 for each of the signal locations, so that entrance buttons 1NB, 2NB, 4NB, and 6NB correspond respectively to the signal locations for signals 1, 2, 4 and 6. Also, an exit button XB is provided for the end of each route, shown as buttons 65 1XB, 2XB, 4XB and 6XB. It is to be understood that the ends of the routes may or may not correspond to the location of the exit buttons on the miniature track diagram, as a route is usually considered to extend from one particular signal 70 to the next signal governing traffic in the same direction, or to some arbitrarily chosen point.

Each entrance button NB is in the form of a knob which is rotatable from a normal position to a position where the index or the knob is in 75

correspondence with the indicator arrow on the inside of the knob, and when such entrance button is so positioned, its associated repeater relay NR is energized through circuits directly controlled by contacts operated by the entrance buttons NB, indicated by dotted lines, and all of which has been shown in detail in my prior application Ser. No. 69,905, filed March 20, 1936.

Within the entrance buttons NB are suitable signal indicators SK shown in Fig. 1 as indicators 1SK, 2SK, 4SK and 6SK. A particular indicator is illuminated when the signal at the corresponding signal location is cleared, all of which is accomplished through means not shown in the present application for the sake of simplicity and a more ready understanding of the present invention.

The exit buttons XB are of the self-restoring push button type and have been connected to push button symbols by suitable dotted lines so as to make the relationship readily apparent.

Also, located on this control signal are suitable track indicators 14TK and 15TK which are illuminated when the corresponding track sections, including track relays 14T and 15T, are occupied. In back of the miniature cross-over switch points ts are suitable lock indicators LKA and LKB which are illuminated when the cross-over ts is included in a proposed route, a cleared route, or in an occupied route.

Route relays.—The entrance button repeater relays NR together with the exit button XB control and select suitable route relays. These route relays have been designated 4—6 for controlling traffic over the main track from signal 4 to signal 6 in both directions, route relays 4—2 for controlling traffic between the signal 5 and the signal 3 over the cross-over in both directions; and route relay 1—2 for controlling traffic between the signal 1 and the signal 2 in both directions.

These route relays suitably select circuits for controlling the switch control relay Z to normal or reverse positions in accordance with the particular route to be set up, and also for closing suitable selections for determining the route codes to be transmitted. The change in position of any route relay causes the initiation of the code transmitter. Preference and sequence between codes is enforced by a suitable code determining bank shown in Fig. 2 as including change relays 1CH, 2CH and 3CH and code determining relays 1CD, 2CD and 3CD. The change relays CH are controlled by starting relays SR, shown as relays 1SR and 2SR. The change relay 3CH is controlled by a manually operable self-restoring starting button SB.

An emergency switch control lever SML is shown in Fig. 1 as associated with the switch control relay Z for operating the switch under certain emergency conditions to be hereinafter pointed out.

The code determining relays CD have associated therewith a manually operable self-restoring cancelling button CNB, and also suitable relays such as relays CHP, CDS, C, FC, NC, PC, EP, SA, 2SA, 1V, 2V, 3V, 4V, 5V, 6V and LV in order to accomplish the proper starting of the code type communication system and the control of the code impulses on the line circuit interconnecting the central office with the field station. The relays of Figs. 2 and 3 and their relationship to each other have been shown in detail in the prior application of Judge and Bushnell, Ser. No. 75 640,062, filed October 28, 1932.

In Fig. 4 certain of the relays of Fig. 3 have their operating circuits shown, such as the stepping relays 1V, 2V, 3V, 4V, 5V, 6V and LV, together with the impulsing relay E and its repeating relay EP which causes the operation of 5 the stepping relay bank and the impulsing of the control line circuit including line wires 10 and 12 which extend to the field location. The current for supplying impulses to the control line circuit is derived from the control office battery CB 10 and is applied in positive or negative impulses as selected by the relays PC and NC respectively.

The line relay F at the central office is repeated by the relays FP and 2FP for each impulse; while the relays SA and 2SA are picked up 15 at the beginning of each cycle of operation and remain picked up until the end of such cycle of operation due to their slow action, although relay SA is only energized during the impulse periods.

The stepping relays V have associated there- 20 with a half-step relay VP.

The line wires 10 and 12 extend to the field locations each of which has a code receiving apparatus as shown in Fig. 5, it being understood that the other field locations have similar 25 apparatus. But it is deemed sufficient for an understanding of the present invention to consider the operation with respect to only a single location.

A line relay F¹ of the three position polarized 30 type repeats the polarity of each of the impulses impressed upon the line circuit. Each impulse irrespective of its polarity is repeated by the line repeating relay FP¹ so long as this field location is in operation. The relays SA¹ and SB¹ 35 are picked up at the beginning of a cycle of operation and are dropped out at the end of a cycle of operation.

A bank of stepping relays 1V¹, 2V¹, 3V¹, 4V¹, 5V¹, 6V¹ and LV¹ operate one step for each of 40 the time spaces between the impulses impressed upon the line circuit including the line wires 10 and 12, while the half-step relay VP¹ changes its position for each impulse.

At the beginning of the cycle of operation, the 45 first group of impulses determines the selection of the station and is registered on the station selecting relays SO¹ and SOS¹; while the latter part of the series of impulses is registered on positive and negative code receiving relays PS and NS. 50

The positive and negative code receiving relays PS and NS have been shown in Fig. 6 as including relays 4PS, 4NS, 5PS, 5NS, 6PS, 6NS, 1PS and 1NS, which relays in turn control the route relays, one for each route, selectively in accordance with the code for particular controlling cycles of operation. These route relays include relays 1—2R, 2—1R, 4—6R, 6—4R, 4—2R and 2—4R. Two stop relays 1—2S and 4—6S are also selectively controlled by the code combination set up on the relays PS and NS for particular cycles of operation.

The switch machine SM is controlled by normal and reverse switch control relays WN and WR, which relays WN and WR are in turn selectively controlled by the route relays, such as relay 1—2R, but during certain emergency control conditions, as hereinafter described, the relays WN and WR are directly controlled by code combinations set up on the relays PS and NS. 70

The route relays, such as relay 1—2R, cooperate with the switch position repeating relay WP to select circuits for the control of signal relays 1G, 2G, 3G, 4G, 5G and 6G which respectively cause their signals 1, 2, 3, 4, 5 and 6 75

to indicate stop when such relays G are deenergized and to indicate clear when the respective relays are energized, all in accordance with the usual practices.

5 *Communication part of the system.*—It is to be understood in connection with the communication part of the system shown in Figs. 2, 3, 4, 5 and 6 that reference should be made to the prior application of Judge and Bushnell, Ser. No. 10 640,062, filed October 28, 1932, for an exhaustive description of such a code type communication system, only that part of such description being pointed out herein as is deemed necessary for an understanding of the present invention. For 15 convenience in comparing the parts of the present disclosure corresponding to the parts of such prior application, the same reference characters have been employed in this disclosure as were used in such prior application.

20 Although the present invention is contemplated as employed in connection with a communication system providing both for the transmission of controls from a central control office to any one of a plurality of field stations, and for the transmission of indications from each of the field stations to the control office, as in the above mentioned application, Ser. No. 640,062, the present invention relates more particularly to the transmission of route controls from the central office 25 to the field stations. Thus, only those parts of the communication system relating more directly to the transmission of controls have been indicated; and similarly, the description relative to the features of the communication system will be 30 directed more particularly to the transmission of controls.

For the transmission of controls, a transmitting equipment is located in the control office and a receiving equipment is located at each of the various field stations. These receiving equipments are connected to the transmitting equipment in the control office by a suitable stepping and control line circuit comprising a stepping line wire 10 and a return line wire 12.

45 The stepping line wire 10 includes a three position biased-to-neutral polar line relay F at the control office and at each of the field stations. The transmitting apparatus at the control office energizes the stepping and control line circuit 50 with a series of time-spaced impulses of polarities selected in accordance with the station code calls and the route control codes to be transmitted.

Each series of time-spaced impulses comprises a predetermined number of impulse and time 55 space periods, which is conveniently termed an operating cycle. In the beginning of such an operating cycle, a slow acting relay SA in the central office (see Fig. 4) and a similar relay SA¹ at each field station (see Fig. 5) is energized. 60 These relays SA are made sufficiently slow acting to be maintained picked up between successive impulses throughout the operating cycle, although their circuits are momentarily opened during each time space period.

65 The application of the successive impulses of a cycle to the stepping circuit causes the operation of the stepping relays V at the control office in synchronism with the stepping relays at each field station, one step for each time space between impulses while the polarity of the impulses 70 serves to select a particular field station and to selectively position the relays PS and NS at the selected station.

75 As the station selecting part of an operating cycle is completely disclosed in the above-men-

tioned application Ser. No. 640,062, only the control part of the operating cycle will be discussed in detail although the station selecting part of the system has been illustrated in the drawings. Also, the station selecting part of the system may be of any suitable type, and for the purpose of describing the present invention only the apparatus at a single station will be considered.

Although, as above mentioned, the stepping banks at the control office and at each of the field stations start in synchronism, only the stepping bank at the control office and at the selected field station operate through a complete cycle of operation, as means is provided at each field station to cause the stepping operation to cease 15 at that station when such station fails to be selected during the station selecting part of the operating cycle.

Keeping in mind this general organization of the complete communication system contemplated in connection with the particular embodiment of the invention illustrated, and particularly that station code calls are transmitted for the selection of a particular station from among a plurality of such field stations, after which a route control code is transmitted to the particular selected station to control the traffic governing device at such station, consideration may now be given to an explanation of the manner in which the codes are set up in the central office 30 and transmitted to the field station to accomplish the setting up of a route through the track layout.

Operation

The system is normally at rest, but may be initiated by the operator for the transmission of controls, as hereinafter explained. While the system is in this condition of rest, or in the period of blank as such condition is sometimes termed, the stepping and control line circuit is 40 normally deenergized; and similarly, the major part of the relays of the system are deenergized. Those relays which are normally energized will have their circuits pointed out when their operation and functions are described.

Although the cross-over TS (see Fig. 7) is usually left in its last operated position, it has been shown in a position for the passage of main line traffic. The signals are normally "at stop" 50 as the signals are illustrated as being of the color-light type, and it is to be understood that the lower or red indicator of each signal is normally illuminated.

With the track sections 14 and 15 unoccupied 55 the track relays 14T and 15T are of course normally picked up.

Referring to Fig. 1, all of the entrance buttons are in their normal positions, so that the system is ready to provide for the establishment and clearing of any of the possible routes through the 60 track layout.

Entrance-exit route interlocking.—As above mentioned, the system of the present invention is of the entrance-exit type so that if the operator desires to set up a route from the signal 1 to the 65 signal 2, he rotates the entrance button 1NB 90° in a clockwise direction, which closes suitable contacts to energize its repeating relay 1NR, and in which position the entrance button 1NB remains until manually restored to put the route 70 to stop, as later described.

After actuating the entrance button 1NB, the operator then glances along the miniature track-way and finds that there are no lock lamps 75 illuminated between such entrance button 1NB and

the exit button 2XB which designates the end of the route and which the operator depresses. In some cases the lock lamp LKB might be illuminated, such as when a route is cleared from 5 the signal 4 to the signal 6, as described in my above-mentioned application Ser. No. 69,905, but under such circumstances, the miniature cross-over ts would indicate the cross-over TS to be in a normal position, so that its operation would 10 not be required to set up the route from the signal 1 to the signal 2, thereby making it perfectly proper for the operator to actuate the exit button 2XB.

The operation of the exit button 2XB occurring contemporaneously with the entrance button 2NB in an operated position, closes a pick-up circuit for route relay 1-2 from (+), through a circuit including front contact 200 of relay 1NR, back contact 201 of route relay 4-2, windings 20 of route relay 1-2, back contact 202 of entrance relay 2NR, back point of exit button 2XB, to (-). The energy which flows in this circuit causes the route relay 1-2 to actuate its polar contacts to the right and to pick up its neutral contacts closing its stick circuit, which allows the operator to release the self-restoring exit button 2XB, by reason of the application of negative potential from (-), through front contact 203 of route relay 1-2, polar contact 204 of route 25 relay 1-2 in a right-hand position, to the right-hand terminal of relay 1-2.

Each of the route relays are picked up in a similar manner and are maintained stuck up dependent upon the return of their respective entrance buttons NB to normal-at-stop positions, which control will be readily apparent from the drawings. It will also be apparent that if a route were set up from the signal 4 to the signal 2, that the route 4-2 would be picked up opening 30 back contact 201 so that the route relay 1-2 could not be picked up. Similarly, the pick-up circuit for the route relay 4-2 includes back contact 199 of the route relay 1-2 so that the route relay 4-2 can not be picked up when the route relay 1-2 is picked up.

As it is possible to have a plurality of parallel routes established at the same time, the pick-up circuit for the route relay 4-6 does not include an interlocking contact on the route relay 1-2, 35 nor does the pick-up circuit for route relay 1-2 include a back contact on route relay 4-6. It is believed that the remaining features of interlock between entrance-exit route buttons will be readily apparent from the drawings, it being understood that only one route relay from among a 40 plurality of route relays for conflicting routes may be picked up at any one time.

Interlock for non-conflicting route codes.— From the above discussion of the communication system, it will be understood that only one code combination can be transmitted over the communication system during any one cycle of operation, and as it is necessary for each route relay, such as relay 4-6, to transmit a distinctive 45 code to the field location for establishing a route, the system is so organized that only one route relay can be effective to condition the code sending relays of the communication system during any one cycle of operation. If all of the route 50 relays were for conflicting routes, then only one route relay could be picked up at a time by reason of the route interlocking above described, so that a further interlock between the codes for the different routes would be unnecessary.

75 However, the usual interlocking plant has many

different groups of conflicting routes, each of which provides for a so-called parallel route. In other words, every interlocking plant usually has a large number of parallel routes, that is, routes which may be set up at the same time and do not conflict, each parallel route of which has associated therewith routes which conflict with such parallel route. Therefore, a parallel route and its conflicting routes may be conveniently termed a group of conflicting routes.

As each group of routes may have a route relay picked up at any time, irrespective of the conditions of the route relays for the remaining groups of the interlocking plant, the system of the present invention provides an interlock between these groups so that only one route relay, although several may be simultaneously picked up, will be capable of conditioning the code transmitting means during any particular cycle of operation.

The present disclosure shows only a single cross-over that provides a route which is conflicting with both of the two parallel routes, but it is to be understood that the association of the parallel routes with other routes may be accomplished in the usual way. Even though only a single field station is used for the control of the cross-over it is necessary to provide an interlock between the parallel routes in the present disclosure because both of the route relays 4-6 and 1-2 may be picked up at the same time.

For the purpose of providing an interlock between different groups of routes (and other purposes later to be pointed out), a code determining bank of relays is provided (see Fig. 2). In this bank, each route group has associated therewith a change relay CH and a code determining relay CD. The relay CH is picked up whenever a route relay in a particular route group changes its position, and remains picked up until the code condition established by the change in position of the route relay has been transmitted over the communication system. The code determining relay CD associated with such change relay is picked up by the relay CH, when the predetermined order of transmission between the groups permits the transmission of a code for that group. In other words, the relays CD for the several groups are so interlocked that only one of these relays may be picked up during any particular operating cycle of the communication system and these relays are picked upon the successive cycles of operation in a predetermined order as determined by the interlocking circuits.

Under certain emergency conditions, herein-after discussed, it becomes necessary to individually operate the track switches and cross-overs, so that this code determining bank includes a change relay CH and a code determining relay CD for each group of track switches which may be individually controlled on particular operating cycles.

It is to be understood that if there were more route groups in the track layout, that each route group would have its additional relay CH and CD connected to the bank in a similar manner as those shown, although such groups might be controlled through the same or another field station. Also, when several field stations are employed, each station has its relay CH and CD for the route groups associated with such station and they are included in the code determining bank of Fig. 2 with the same kind of an interlock as shown for the relays 1CH, 2CH, 3CH, 1CD, 2CD and 3CD.

Regardless of the number of stations, and the 75

groups of routes for such stations, a cancelling button CNB provides that any change which has been stored in the code determining bank may be manually cancelled, so that the operator may 5 set up an entirely new set of control conditions.

Initiation of the system.—We may now consider how the picking up of a route relay, such as route relay 1—2, effects the storage of a change in its associated relay 2CH so as to accomplish 10 the transmission of a route control code.

The relay 2SR is normally energized by a circuit closed from (+), through a circuit including back contact 205 of route relay 1—2, lower winding of relay 2SR, front contact 206 of relay 2SR, 15 to (—).

When the route relay 1—2 is picked up, as above described, the opening of back contact 205 opens the energizing circuit for the lower winding relay 2SR, and closes an energizing circuit 20 for its upper winding from (+), through a circuit including front contact 205, upper winding of relay 2SR, front contact 206 of relay 2SR, to (—), providing that the relay 2SR is not already 25 dropped away due to its momentary deenergization between the opening of back contact 205 and the closure of front contact 205. If current flows in the upper winding of relay 2SR, it reverses the magnetism in the relay 2SR which causes such magnetism to pass through zero, because 30 the upper and lower windings are differentially connected as indicated by the arrows within their windings. Thus, the relay quickly drops away and remains dropped away as both circuits are now open at front contact 206.

35 The dropping away of the relay 2SR closes a pick-up circuit for the change relay 2CH from (+), through a circuit including back contact 207 of relay 2SR, wire 208, winding of relay 2CH, front contact of cancelling button CNB, to (—).

40 The current which flows in this circuit causes the relay 2CH to immediately pick up and close a stick circuit from (+), through a circuit including back contact 209 of relay 2CD, front contact 210 of relay 2CH, windings of relay 2CH, 45 front contact of cancelling button CNB, to (—).

45 As soon as the change relay 2CH picks up, it also closes a circuit for restoring the relay 2SR from (+), through a circuit including front contact 205 of route relay 1—2, upper winding of 50 relay 2SR, wire 211, front contact 212 of relay 2CH, to (—). When the relay 2SR picks up, the closure of its front contact 206 connects (—) to the right-hand terminal of its upper winding thereby closing its stick circuit to maintain the 55 relay 2SR picked up irrespective of the subsequent opening of contact 212 of relay 2CH. The opening of back contact 207 of relay 2SR removes the (+) from the pick-up circuit of the relay 2CH, but the relay 2CH remains picked up 60 by reason of its stick circuit, above pointed out.

65 It will be readily apparent that the shift of the contact 205 from a front point to a back point will cause the drop away of the relay 2SR in a similar manner as the shift from the back point to the front point, which deenergization of the relay 2SR will in turn cause the picking up of the relay 2CH and its own restoration. In other words, the relay 2SR is dropped away to 70 pick up the relay 2CH and is again restored by the picking up of the relay 2CH regardless of whether the route relay 1—2 is picked up or whether it is dropped away.

75 The relay 2SR is provided with a normally energized holding circuit closed from (+), through a circuit including back contact 213 of route

relay 4—6, back contact 214 of route relay 4—2, lower winding of relay 1SR, front contact 215 of relay 1SR, to (—). It will be readily apparent that the picking up of either the route relay 4—6 or the route relay 4—2, only one of 5 which can be picked up at the same time, shifts the application of (+) to the upper winding of relay 1SR by either the closure of front contact 213 or the front contact 214 of these two route relays respectively, so that the relay 1SR will 10 drop away whenever a change in these route relays occurs.

The dropping away of the relay 1SR closes a pick-up circuit for the relay 1CH from (+), through a circuit including back contact 216 of 15 relay 1SR, wire 217, winding of relay 1CH, front contact of the cancelling button CNB, to (—). The picking up of the relay 1CH closes its stick circuit from (+), through a circuit including back contact 23 of relay 1CD, front contact 24 of 20 relay 1CH, windings of relay 1CH, front point of cancelling button CNB, to (—).

25 The picking up of relay 1CH completes a restoring circuit for the relay 1SR by applying (—), through front contact 218 and wire 219 to the right-hand terminal of relay 1SR, which is completed with route relays 4—6 and 4—2 either both deenergized or one or the other picked up.

30 In the event that the operator desires to transmit a switch control code in accordance with the position of the lever SML, as later described, he must depress the self-restoring starting button SB to close a pick-up circuit for the relay 3CH from (+), through a circuit including a back 35 contact of starting button SB, wire 220, windings of relay 3CH, front contact of cancelling button CNB, to (—). The picking up of the relay 3CH closes its stick circuit from (+), through a circuit including back contact 152 of relay 3CD, 40 front contact 151 of relay 3CH, windings of relay 3CH, front contact of cancelling button CNB, to (—).

45 If several of the change relays CH are energized at the same time, only one of the code determining relays CD can be picked up during a 50 cycle of operation of the communication systems, which will probably be best understood after a consideration of the manner in which a particular code determining relay CD is picked up when only one relay CH has been conditioned.

55 Assuming that the operator desires to set up the route from the signal 1 to the signal 2, as above considered, the picking up of the route relay 1—2 causes the dropping of the relay 2SR followed by the picking up of the relay 2CH which in turn restores the relay 2SR.

60 The picking up of the relay 2CH also supplies energy to the change repeating relay CHP by a circuit closed from (+), through a circuit including back contact 25 of relay SA, back contact 26 of relay FC, upper winding of relay CHP, wire 223, front contact 224 of relay 2CH, to (—). As soon as the relay CHP picks up, it is energized through its stick circuit from (+), through 65 a circuit including back contact 30 of relay LV, front contact 31 of relay CHP, lower winding of relay CHP, to (—).

70 The picking up of relay CHP closes front contact 63 so as to supply energy from (+), to the heel of contact 64 of relay EP so that although the contact 64 is intermittently opened throughout the cycle of operation, the relays 2CD and CDS remain energized until the relay CHP is 75 dropped away upon the opening of contact 30.

at the end of the cycle of operation when the last step relay LV is picked up. It will be noted that the relay CHP could not be picked up if the system were in operation because of the open condition of back contact 25 of relay SA, nor could the relay CHP be picked up if a field station has already registered a field start because of the open condition of back contact 26 of relay FC, which relay FC registers such a field start as 10 has been disclosed in the above-mentioned application Ser. No. 640,062.

The picking up of the relay CHP closes its front contact 29 which completes a pick-up circuit for the control office starting relay C from 15 (+), through a circuit including back contact 28 of relay SA, front contact 29 of relay CHP, windings of relay C, to (-). As soon as the relay C picks up, it closes its stick circuit from (+), through a circuit including back contact 20 32 of relay 2SA, front contact 33 of relay C, windings of relay C, to (-).

At the start of the cycle of operation, the relay SA picks up first followed by its repeater 2SA so that front contact 28 is closed before back contact 25 32 opens, thereby maintaining the stick circuit for the relay C throughout the cycle of operation. But at the end of the cycle of operation, the relay SA drops away before its repeater relay 2SA drops thereby opening front contact 28 before back contact 32 closes so that the stick circuit for the relay C is momentarily opened and the relay drops away.

The picking up of the relay C completes a pick-up circuit for the relay 2CD by the closure of its front contact 35, which pick-up circuit is closed from (+), through a circuit including back contact 30 of relay LV, front contact 35 of relay C, back contact 34 of relay 2SA, back contact 36 of relay CDS, back contact 37 of relay 3CH, front contact 38 of relay 2CH, upper winding of relay 2CD, front contact of cancelling button CNB, to (-).

As soon as the relay 2CD picks up, its stick circuit is closed from (+), through a circuit including back contact 64 of impulse repeating relay EP, windings of relay CDS, front contact 221 of relay 2CD, lower winding of relay 2CD, front contact of cancelling button CNB, to (-). The current which flows in this stick circuit not only holds the relay 2CD energized, but also picks up the code determining stick relay CDS which opens its back contact 36 to prevent any other relay CH (which is more superior to the relay 2CH) from picking up its relay CD, such as for example, the 55 relay 3CD by the relay 3CH closing its front contact 37. It is of course apparent that the opening of back contact 38 of relay 2CH prevents an inferior change relay CH from picking up its relay CD.

60 The picking up of the relay 2CD shifts the supply of energy for the stick circuit of relay 2CH from (+), through back contact 209 of the make-before-break contact 209, to a circuit closed from (+), through a circuit including back contact 66 of stepping relay 6V, wire 222, front contact 209 of relay 2CD, front contact 210 of relay 2CH, windings of relay 2CH, front contact of cancelling button CNB, to (-). This stick circuit for the relay 2CH remains closed until the system operates through a cycle opening the back contact 66 on the sixth step of the cycle. This releases the relay 2CH in which condition it remains until a subsequent change is registered on the storing relay 2SR. Thus, with the relays 2CD and C both 75 picked up, the system is conditioned to transmit

impulses for a cycle of operation. However, it is considered expedient to briefly consider the step-by-step operation in the central office with respect to Fig. 4 before considering how the distinctive characters of the impulses are selected in 5 accordance with the codes to be transmitted.

With the relay C and CD both picked up, a pick-up circuit is closed for one or the other of the relays PC or NC, as will be presently described, but considering for the moment that one of these 10 relays is picked up without going into the detail of its manner of control, it will be apparent that a positive or negative impulse is placed upon the control line circuit including the line wires 10 and 12.

If the relay PC is picked up the control office battery is connected into the line circuit to transmit a positive impulse; while if the relay NC is picked up the control office battery CB is connected into the circuit so as to transmit a negative impulse.

The application of an impulse upon the stepping and control line circuit energizes the line relays F in accordance with the particular polarity, but irrespective of the polarity of such impulse the line repeating relays FP are energized to repeat the impulse.

In the central office, the closure of front contact 68 of relay FP energizes its repeating relay 2FP which in turn through contact 69 energizes 30 relay SA, which is also repeated upon the closure of its contact 70 by relay 2SA.

As soon as the relay SA picks up a circuit is closed for picking up the half-step relay VP from (+), through a circuit including front contact 71 of relay SA, front contact 72 of relay 2FP, back contact 73 of relay 1V, windings of relay VP, to (-). As soon as the relay VP picks up, it closes one of its stick circuits from (+), through a circuit including front contact 71 of relay SA, front contact 74 of relay VP, back contact 73 of relay 1V, windings of relay VP, to (-).

With the relay VP picked up, a pick-up circuit is closed for the relay E as soon as relay 2SA has picked up from (+), through a circuit including 45 front contact 90 of relay 2SA, front contact 92 of relay VP, back contact 93 of relay 1V, upper winding of relay E, to (-).

The relay E closes front contact 95 and energizes its repeating relay EP which in turn opens 50 back contact 52 included in the stepping and control line circuit causing the end of the first impulse period.

Therefore, it is apparent that the duration of the first impulse includes the successive pick-up 55 periods of the relays F, FP, 2FP, SA, 2SA, E and EP.

The deenergization of the stepping and control line circuit is repeated by the relays F, FP and 60 2FP, but the relay SA and 2SA, being slow acting, remain picked up during the time space periods between impulses so that they remain steadily picked up throughout the cycle of operation.

When the relay 2FP drops away, a pick-up circuit is closed for the stepping relay 1V from 65 (+), through a circuit including front contact 75 of relay SA, back contact 76 of relay 2FP, front contact 77 of relay VP, back contact 78 of relay 2V, windings of relay 1V, to (-). As soon as the relay 1V picks up, it closes a stick circuit, 70 which is maintained closed throughout the remainder of the cycle, from (+), through a circuit including front contact 75 of relay SA, front contact 79 of relay 1V, windings of relay 1V, to (-).

The picking up of the relay 1V opens the pick- 75

up and stick circuits previously pointed out for the relay VP, but another holding circuit has been closed prior to the picking up of the relay IV by the closure of back contact 72 of relay 2FP 5 so that the relay VP remains picked up by reason of a stick circuit from (+), through a circuit including front contact 71 of relay SA, back contact 72 of relay 2FP, front contact 80 of relay VP, windings of relay VP, to (-). This holding circuit provides that the relay VP is held up until the relay 2FP is again picked up.

The picking up of relay IV opens back contact 93 which deenergizes the relay E, which in turn deenergizes the relay EP by opening contact 95. 15 As soon as the relay EP drops away, the contact 52 in the line circuit is closed so that the next impulse is impressed upon the line circuit the character of which is determined by the particular pulsing relay PC or NC which has been picked up during the time that the relay EP has maintained the line circuit open.

Therefore, it will be apparent that the duration of the time space period includes the drop away periods of the relays F, FP, 2FP, E and EP as well 20 as the pick up period of the proper stepping relay, in this case stepping relay IV.

The application of the second impulse upon the line circuit causes the energization of the relay F at the control office and at each field station 30 which repeats the polarity of the impulse. However, irrespective of the polarity of the impulse the relay FP in the central office and the relay 2FP are successively picked up. As soon as the relay 2FP picks up, the relay VP drops away by 35 reason of the opening of its stick circuit including back contact 72.

Upon the dropping away of the relay VP, the next energizing circuit for the relay E is closed from (+), through a circuit including front contact 90 of relay 2SA, back contact 92 of relay VP, back contact 96 of relay 2V, front contact 97 of relay IV, lower winding of relay E, to (-). This energization of the relay E is repeated by the relay EP which marks the end of the second impulse by the opening of back contact 52.

Therefore, it will be apparent that the second impulse is of a duration which includes the pick up periods of the relays F, FP, 2FP, E and EP as well as the drop-away period of the relay VP. All 50 of the subsequent impulses are of the same duration, while all of the time spaces are similarly of the same duration as described in connection with the first time space period. The first impulse period is the longest impulse in the cycle for 55 the purpose of picking up the cycle marking relays SA and 2SA in the central office and corresponding relays at the field stations, such as relays SA¹ and SB¹ of Fig. 5.

It is believed that it will be readily apparent 60 how the step-by-step operation continues throughout the cycle of operation, a stepping relay being picked up upon each dropping away of the relay 2FP and the relay VP changing its position upon each picking up of the relay 2FP.

65 During the last impulse of the cycle of operation, the VP relay is picked up, which closes a pick-up circuit for the relay LV as the stepping relay 6V was picked up upon the preceding time space period. This circuit is closed from (+), 70 through a circuit including front contact 88 of relay VP, jumper 225, front contact 89 of relay 6V, windings of relay LV, to (-). As soon as the relay LV picks up, its stick circuit is closed from (+), through a circuit including front contact 75

90 of relay 2SA, front contact 91 of relay LV, windings of relay LV, to (-).

It is noted that the jumper 225 provides for the closure of the pick-up circuit of relay LV upon the picking up of relay VP. This is true when 5 the stepping relays IV, 2V, 3V, etc. are an even number, as in this disclosure. However, if an odd number of stepping relays V were employed, the jumper 225 would be in its lower position so as to include the back contact 88 of relay VP 10 instead of front contact 88.

It will be apparent that relay LV is stuck up upon front contact 90 of relay 2SA, which is the last slow acting cycle demarking relay to drop away at the end of the cycle, therefore rendering 15 the relay LV the last relay in the system to restore to normal.

The picking up of the relay VP with the stepping relay 6V picked up closes an energizing circuit for the relay E, from (+), through a circuit 20 including front contact 90 of relay 2SA, front contact 92 of relay VP, front contact 226 of relay 6V, upper winding of the relay E, to (-). This energization of the relay E is repeated by the relay EP upon the closure of front contact 95, 25 which relay EP in turn opens the line circuit at back contact 52 marking the end of the last impulse of the cycle of operation. The relay EP is maintained energized by reason of the maintained energization of the relay E, even upon the 30 dropping away of the relay VP when the relay SA drops for the end of the cycle, by reason of an energizing circuit closed from (+), through a circuit including front contact 90 of relay 2SA, back contact 92 of relay VP, front contact 106 35 of relay LV, lower winding of relay E, to (-).

Having considered how the step-by-step operation takes place so as to impress impulses upon the line circuit, we may now consider how the distinctive characters of these impulses are selected in accordance with the codes to be transmitted. 40

Transmission of station and route codes.—As above mentioned, the system of the present invention is contemplated as being used with a 45 communication system having a large number of field stations, although only one has been shown in the present disclosure, the remaining stations being similar to the one shown. Thus, the first part of an operating cycle must have 50 impulses of polarities selected in accordance with the code call of the station to which the route code is to be transmitted, while the later or remaining impulses of the cycle of operation must have their polarities selected in accordance with 55 the particular route code then set up for that station.

For convenience in considering the various codes which are used in the present disclosure and for the various possible codes which may be 60 set up, a typical code table has been shown below. This typical code table shows all of the route control codes which are employed at the station shown in Figs. 5, 6 and 7, but preceding these route control codes only that station selecting code required for the station under consideration has been shown. The first three impulses of a cycle are shown as used for station selection purposes, while the last four impulses are shown as used for route control codes. When the three 65 impulses for station selection are combined in the different possible combinations according to the exponential law of the Baudot code, eight distinctive station code calls are provided. For each of these station codes, sixteen route control 70 codes are provided. For each of these route control 75

codes are provided by the four control impulses. Therefore, if the full code capacity of the seven impulse cycle were employed, the code table would have 128 codes, but for the sake of simplicity only the codes employed at the station shown have been included in the typical code table.

Typical code table

10	Code No.	Station selection			Route control codes			Use
		1	2	3	4	5	6	
15	1	+	+	-	+	+	+	+
	2	+	+	-	+	+	+	1-2R
	3	+	+	-	+	-	+	2-1R
	4	+	+	-	+	-	+	
	5	+	+	-	+	-	+	
	6	+	+	-	+	-	+	
	7	+	+	-	+	-	+	WR
20	8	+	+	-	+	-	+	WN
	9	+	+	-	+	-	+	4-6S
	10	+	+	-	+	-	+	4-2R
	11	+	+	-	+	-	+	6-4R
	12	+	+	-	+	-	+	4-6R
	13	+	+	-	+	-	+	1-2S
	14	+	+	-	+	-	+	2-4R
25	15	+	+	-	+	-	+	
	16	+	+	-	+	-	+	

With reference to Fig. 2, the code determining relay 1CD is provided with station selecting code jumpers 227, 228 and 229; code determining relay 2CD is provided with station selecting code jumpers 230, 231 and 232; and, the code determining relay 3CD is provided with station selecting code jumpers 233, 234 and 235.

The relays 1CD and 3CD are respectively provided with control code jumpers 236 and 237.

The relays PC and NC have their right-hand terminals connected to (-), while their left-hand terminals are connected to buses 47 and 48 which extend through the code determining bank of Fig. 2 and the route relays of Fig. 1 as well as the Z relays associated with the emergency switch control levers, such as lever SML.

Upon the picking up of the cycle controlling relay C and the particular code determining relay CD up for the cycle of operation to ensue, the circuit selections are conditioned so that the station selecting code jumpers for the relay CD which is picked up are successively rendered effective to energize the relays PC and NC for the successive impulses after which the connections on the route relays, or the Z relays are successively rendered effective to position the relays PC and NC for the remaining successive impulses of the cycle of operation. It is believed that this functioning of the system will be readily understood by a consideration of the manner in which the station selecting code is impressed upon the line circuit by the code jumpers 230, 231 and 232 of the code determining relay 2CD

and by the connections associated with the route relay 1-2 assuming such relay to be picked up to clear a route from the signal 1 to the signal 2.

When the relay 2CD picks up following the picking up of the cycle controlling relay C, energy is applied to the code sending relay PC in accordance with the position of the code jumper 230 to determine the polarity of the first impulse by a circuit closed from (+), through a circuit including front contact 41 of relay C, back contact 238 of relay 6V, back contact 239 of relay 5V, back contact 240 of relay 4V, back contact 241 of relay 3V, back contact 242 of relay 2V, back contact 243 of relay 1V, code bus 244, front contact 245 of relay 2CD, code jumper 230, bus wire 47, windings of relay PC, to (-).

This impresses a positive impulse upon the line circuit for the first impulse period. By referring to the typical code table, it will be apparent that this agrees with the character of the impulse for the first impulse for station selection.

Upon the picking up of the relay 1V during the first time space period of the cycle, contact 243 shifts the application of energy to the code bus 246, which through front contact 247 of relay 2CD allows the code jumper 231 to determine that the next impulse applied to the line circuit shall be positive by energizing the relay PC over the bus 47.

Upon the picking up of the relay 2V during the second time space period of the cycle, contact 242 shifts the application of energy to the code bus 248 which through front contact 249 of relay 2CD allows the code jumper 232 to determine that the next impulse applied to the line circuit shall be negative by energizing the relay NC over the bus 48.

The route relay 1-2 now determines the character of the remaining impulses of the cycle. As the route desired to be set up is from the signal 1 to the signal 2, the route code employed is 25 the code No. 3 in the typical code table, from which table it will be apparent that the following description of the successive circuits set up on each of the steps will select the code characters for this code No. 3.

Upon the picking up of the relay 3V during the third time space period of the cycle, contact 241 shifts the application of energy to the code bus 250 which through front contact 254 of relay 2CD over the wire 258 and through front contact 262 of route relay 1-2 causes the fourth impulse applied to the line circuit to be positive by energizing the relay PC over the bus 47.

Upon the picking up of the relay 4V during the fourth time space period of the cycle, contact 240 shifts the application of energy to the code bus 251 which through front contact 255 of relay 2CD over the wire 259 and through front contact 263 of route relay 1-2 causes the fifth impulse applied to the line circuit to be positive by energizing the relay PC over the bus 47.

Upon the picking up of the relay 5V during the fifth time space period of the cycle, contact 239 shifts the application of energy to the code bus 252, which through front contact 256 of relay 2CD over the wire 260 and through front contact 264 of route relay 1-2 causes the sixth impulse applied to the line circuit to be negative by energizing the relay NC over the bus 48.

Upon the picking up of the relay 6V during the sixth time space period of the cycle, contact 238 shifts the application of energy to the code bus 253 which through front contact 257 of relay 2CD over the wire 261 and through front contact 265 of route relay 1-2 and polar contact 266 of route relay 1-2 in a right-hand position causes the seventh impulse applied to the line circuit to be positive by energizing the relay PC over the bus 47.

Thus, the route relay 1-2 accomplishes the transmission of the code No. 3 for clearing a route from the signal 1 to the signal 2.

We might consider at this time that the operator after having cleared this route desires to put the route to stop either because of a change in his plans for the on-coming train or because the train has passed over the route and he desires to change the route set up for a succeeding train. To do this, all that is nec-

sary is for the operator to restore the entrance button 1NB to its normal vertical position de-energizing its repeating relay 1NR and opening front contact 200 which in turn deenergizes the 5 route relay 1-2.

The deenergization of the route relay 1-2 causes the picking up of the relays 2CH and 2CD providing the operating conditions of the communication system are proper, as previously de-10 scribed for the transmission of a clear code, so that a code is transmitted with the contacts of the route relay 1-2 deenergized.

With reference to the typical code table, the stop code has been selected as code No. 13 so 15 that the back contacts 262, 263, 264 and 265 of the route relay 1-2 are so connected to the buses 47 and 48 as to provide this code No. 13. In this connection it might be well to know that the clearing code No. 3 is in the first half of the 20 route control codes while the stop code is in the last half, which causes the fourth impulse in the code to differ for the two complete codes. This makes necessary the wire connection from the heel of contact 254 of relay 2CD through wire 25 258 and contact 262 of the route relay 1-2 to the buses 47 and 48. But, if two codes were employed in the same half of the route control codes, such selection might be eliminated and a jumper connected from the heel of contact 254 to 30 one or the other of the buses 47 and 48, similarly as for a station code jumper. This has been illustrated specifically in connection with the route codes for the route relays 4-2 and 4-6 by the provision of the route control jumper 35 236. These two methods of connection have been shown for the purpose of illustrating that the route control codes for the different routes may be selected as desired from the complete route control code table, and that the various 40 routes do not necessarily require particular codes.

It may also be noted that if the route relay 1-2 were picked up in response to the operation of the entrance button 2NB and the exit button 1XB so as to actuate its polar contacts 45 to left-hand positions, then the code No. 4 will be applied. The only difference between code Nos. 3 and 4 is found in the character of the seventh impulse which is determined by the position of the polar contact 266. Although this section of codes for the two routes having opposite directions differ only by the character of a single impulse, it is to be understood that codes may be selected which differ by the character of two or more impulses, if so desired by providing 55 additional polar contacts on the route relay 1-2 and suitable circuit connections. Also, the difference between codes selected for opposite directions in a route may be provided on any impulse or impulses desired, which has been illustrated more specifically with respect to the route relay 4-2 which has its polar contact 267 provide the difference between the two codes for opposite directions for the route from signal 4 to signal 2 on the fifth impulse of the cycle. 60

65 It is believed that it will be readily understood by analogy to the description given in connection with the route relay 1-2 how the other route relays 4-6 and 4-2 provide for the transmission of their route control codes when the 70 code determining relay 1CD is picked up as previously described. However, it is believed that it will be expedient to point out the reason for the chain stitch interlock between the contacts 268, 269 and 270 of route relay 4-2 with the 75 contacts 271, 272 and 273 of the route relay 4-6.

It was mentioned above that only one of the route relays 4-6 and 4-2 may be picked up at the same time, so that both route relays may be associated with a single code determining group including relays 1CH and 1CD. Also, as these route relays 4-6 and 4-2 govern routes which are conflicting routes, the same code may be employed for putting both routes to stop, but as the picked up condition of either route relay is to transmit a code for clearing its corresponding route, the picking up of either relay must also prevent the transmitting of the stop code. Therefore, the code buses 251, 252 and 253 are selectively connected to the buses 47 and 48 through back contacts of both of the route relays 4-6 and 4-2 so that the picking up of either route relay connects code buses 251, 252 and 253 selectively to the buses 47 and 48 in accordance with the particular clearing route code of the route relay then picked up and disconnects the stop code connections which are in accordance with the code No. 9 in the typical code table.

Transmission of emergency switch control code.—The manual individual control of a track 25 switch is desirable under certain emergency conditions which arise in an interlocking plant, such as the operation of track switch back and forth when it fails to entirely complete an operating stroke due to ice or lumps of coal or the like, 30 and such as the setting up of the trackway for the passage of hand cars and the like although it is not desired to clear the signal for such a route. This manual control is provided in accordance with the present invention in such a 35 way as to be possible so long as the track switch is free to be operated, but when it is included in a route which is cleared by the entrance-exit control, the operation of such switch by the emergency switch machine control lever SML is 40 effectively prevented.

Assuming that all of the routes are at stop, let us consider the operation in response to the use of this emergency switch control lever SML. The operation of lever SML to its reverse position 45 closes contacts 274 and 275 to complete a circuit from (+), through the lower winding R of the relay Z, to (-); while the operation of the lever SML to its normal position closes contacts 276 and 277 to complete a circuit from (+), 50 through the upper winding N of relay Z, to (-).

The energization of the reverse winding of the relay Z actuates the polar contacts of this relay to left-hand positions and picks up its neutral contacts; while the energization of the normal winding N of the relay Z actuates its polar contacts to right-hand positions and picks up its neutral contacts. This is because the windings N and R are differentially connected. Therefore, if both of the windings N and R of the relay Z are 60 energized at the same time the magnetic flux produced to act upon the armature is substantially zero because of the neutralizing effect of one winding upon the other. This feature of operation comes into effect in the event that a 65 route relay, such as route relay 1-2, is picked up closing front contact 278 which applies energy to the normal winding N of the relay Z so that if the lever SML is operated at that time to its reverse position, the reverse winding R is 70 also energized and the contacts of the relay Z drop away. With the contacts 279, 280 and 281 of the relay Z dropped away, such relay cannot transmit a code as will presently be described.

Similar operation occurs when the route relay 75

- 4-2 is picked up closing the contact 282 to energize reverse winding R of the relay Z if lever SML is operated to its normal position to also energize the normal winding N of the relay Z.
- 5 In other words, if a route relay is picked up at the same time with the emergency lever SML in an operated position, the contacts of the relay Z assume deenergized positions and cannot effectively transmit a code.
- 10 If, however, all routes are at stop involving the associated track switch or crossover, then the operation of the lever SML to the normal or reverse positions correspondingly energizes the relay Z and conditions it to transmit a switch control code, which is effected when the operator actuates the self-restoring starting button SB to pick up the change storing relay 3CH, as previously pointed out, for causing the initiation of the system into a cycle of operation.
- 15 The first three impulses of the code are determined in accordance with jumpers 233, 234 and 235 to transmit the station code call (+) (+) (-) as assigned in the typical code table. From the typical code table it will also be observed that the codes Nos. 7 and 8 are selected for the control of the reverse and normal operation of the track switch. As the fourth impulse in each of these codes is the same, then a control jumper such as 231 is employed to determine the character of the fourth impulse. The fifth and sixth impulses could likewise be determined by a control jumper in place of the extension of the code buses through the Z relay, but it may be desirable to control additional switches through the same code determining group, that is, relays 3CH and 3CD, and in order to be able to obtain the additional combinations, it is necessary to carry the selections through any other relays Z in a chain stitch fashion from the back contacts 279, 280 and 281 of the relay Z in a similar fashion as has been provided in connection with contacts 268, 269, 270, 271, 272 and 273 for the route relays 4-2 and 4-6.

However, for the purpose of the present disclosure, the code buses 251, 252 and 253 have been shown respectively carried through front contacts 283, 284 and 285 of the relay 3CD over wires 286, 287 and 288 to the contacts 279, 280 and 281 respectively. With the relay Z picked up, the connections from contacts 279 and 280 provide that the fifth and sixth impulses shall be negative while the seventh impulse is positive if the relay Z is actuated to a normal position and is negative if the relay Z is actuated to a reverse position as determined by the polar contact 289.

When the switch control code has been transmitted, the system of course restores to its normal condition dropping the relays 3CD and 3CH, as previously described. However, the relay Z will remain in the position to which it is actuated by the lever SML until this lever SML is restored to its central normal position.

Field station reception of codes.—Before considering how the route control codes are received at the field station, it is considered expedient to briefly point out the operation of the field station code receiving unit, although reference may be made to the above-mentioned application Ser. No. 640,062, filed October 28, 1932 for a detailed description of station selection and the like.

The first impulse of a cycle of operation impressed upon the control and stepping line circuit including line wires 10 and 12, is repeated by the line relay F¹ so as to energize the repeating relay FP¹ through the medium of the polar contact 101

irrespective of the polarity of the impulse. This first impulse is also sufficiently long to pick up the slow acting relay SA¹, which remains picked up throughout the operating cycle either by receiving momentary energizations through front contact 107 of relay FP¹ or from the polar contact 101 of relay F¹. So long as the station is capable of being selected or has been selected, the relay SO¹ is picked up and the relay FP¹ continues to operate to repeat the impulses by 10 the line relay F¹, but when the station relay SO¹ drops away, then the relay FP¹ ceases operation. The stepping relays V¹ and half-step relay VP¹ are controlled by the relay FP¹ in a manner explained in detail for the stepping bank in the 15 control office.

The station selecting relay SO¹ is picked up at the beginning of the cycle of operation and is maintained selectively picked up dependent upon the character of the first three impulses which 20 for this station have been selected as (+) (+) (-), as seen in the typical code table. This code combination has been set up by the station code selecting jumpers 111, 112 and 113 for the first three impulses in the cycle of operation respectively. At the end of the station selecting impulses, the third stepping relay 3V¹ is picked up rendering the jumper 129 effective to maintain the station selecting relay SO¹ picked up throughout the remainder of the cycle of operation until 30 the last stepping relay LV¹ is picked up opening back contact 131.

Thus, the stepping relay bank operates throughout the cycle and the picked up condition of the station selecting relay SO¹ provides 35 that the decoding relays NS and PS may be positioned in accordance with the character of the route control code impulses. All of the route control decoding relays NS and PS are shown in Fig. 6, but as typical of the manner in which these 40 relays are selectively picked up in accordance with the character of the code impulses, only the pick-up circuits for the relays 7PS and 7NS have been shown in Fig. 5.

More specifically, if the seventh impulse of the 45 cycle of operation is a positive (+) impulse, then the polar line relay F¹ has its polar contacts operated to the right and the stepping relay 6V¹ having been picked up, a circuit is closed from (+), through a circuit including front contact 118 of station selecting relay SO¹, polar contact 114 of line relay F¹ in a right-hand position, front contact 290 of stepping relay 6V¹, lower winding of decoding relay 7PS, to (-). When this relay 50 7PS is picked up, it is maintained picked up by 55 a stick circuit (see Fig. 6) closed from (+), through a circuit including front contact 291 of station selecting relay SO¹, front contact 292 of relay 7PS, upper winding of relay 7PS, to (-).

This stick circuit is maintained closed throughout the cycle of operation, but as the picking up of the last stepping relay LV¹ causes the station selecting relay SO¹ to drop away, a front contact 293 on the relay LV¹ is provided to continue to energize the stick circuit until such slow 65 acting last stepping relay LV¹ drops away. There is no interval of opening in the stick circuit as the relay LV¹ picks up before the relay SO¹ drops away.

In a similar manner, if the seventh impulse is 70 negative in character, a pick-up circuit is closed for the decoding relay 7NS (see Fig. 5) from (+), through a circuit including front contact 118 of relay SO¹, polar contact 114 of relay F¹ in a left-hand position, front contact 294 of stepping relay 75

6V¹, lower winding of relay 7NS, to (-). When the decoding relay 7NS is picked up, it is maintained stuck up throughout the cycle of operation by a stick circuit similar to that provided for the relay 7PS, namely, a circuit closed from (+), through a circuit including front contact 291 of relay SO¹, front contact 295 of relay 7NS, upper winding of relay 7NS, to (-).

It will be readily apparent that each of the decoding relays 4PS, 5PS, 6PS and 7PS are respectively connected to front contacts 115, 296, 297 and 290 of the stepping relays shown in Fig. 5; while the decoding relays 4NS, 5NS, 6NS and 7NS are respectively connected to front contacts 119, 298, 299 and 294 of the stepping relays shown in Fig. 5.

It will also be apparent from Fig. 6 that each of the relays PS and NS have similar stick circuits controlled by the contacts 291 and 293 of the relays SO¹ and LV¹ respectively.

Reception of route control code.—Let us assume that the operator has operated the entrance button 1NB and the exit button 2XB picking up the route relay 1—2 and therefore causing the transmission of the code No. 3 in the typical code table. The first three impulses in this code select the station, as above pointed out, causing the station selecting relay SO¹ to be maintained up only at this particular field station for the cycle of operation under consideration, and during the last four impulses of which the relays 4PS, 5PS, 6NS and 7PS are respectively picked up and maintained picked up until the end of the cycle of operation and the dropping of the last stepping relay LV¹, at which time the code set up by these relays is executed to the proper route relays for controlling the traffic controlling devices.

With this code set up upon the decoding relays, an execution circuit is closed during the time that the last stepping relay LV¹ is picked up subsequent to the dropping of the slow acting relay SA¹. It will be apparent from Fig. 5 that this time period will be equal to the dropping away time of the relay LV¹. This execution circuit for the particular code assumed to be set up is closed from (+), through a circuit including back contact 300 of relay SA¹, front contact 301 of relay LV¹, back contact 302 of relay 4NS, back contact 303 of relay 5NS, back contact 304 of relay 6PS, back contact 305 of relay 7NS, front contact 306 of relay 4PS, front contact 307 of relay 5PS, front contact 308 of relay 6NS, front contact 309 of relay 7PS, wire 310, back contact 311 of route relay 2—1R, lower winding of route relay 1—2R, to (-).

As soon as the route relay 1—2R picks up, it is maintained picked up by a stick circuit closed from (+), through a circuit including back contact 312 of stop route relay 1—2S, front contact 313 of route relay 1—2R, upper winding of route relay 1—2R, to (-).

Thus, at the end of the execution period and the opening of the execution circuit just pointed out, all of the decoding relays PS and NS drop away to their normal positions, but the route relay 1—2R remains picked up due to its stick circuit so as to set up its route and clear the signal for such route.

70 The picking up of the route relay 1—2R closes an energizing circuit for the normal switch controlling relay WN from (+), through a circuit including front contact 314 of route relay 1—2R, bus wire 345, lower winding of relay WN, to (-). 75 When the relay WN is picked up, it is maintained

picked up by a stick circuit closed from (+), through a circuit including front contact 315 of relay WN, back contact 316 of relay WR, upper winding of relay WN, to (-). This stick circuit maintains the relay WN in a picked up condition until the reverse switch control relay WR is picked up for some other route in response to a route relay, such as relay 4—2R, or in response to the reception of an emergency switch control code as will be explained hereinafter.

With the relay WN picked up, the normal switch machine control circuit is closed from (+), through a circuit including front contact 317 of track relay 15T, front contact 318 of track relay 14T, front contact 319 of lock relay L, back contact 320 of relay WR, front contact 321 of relay WN, through the switch machine SM, to (-). This causes the normal operation of the switch machine SM and the operation of the crossover TS to normal positions which is repeated by the relay WP.

With the crossover TS in a normal position, either when it has been in such position initially or when it has just operated to such position, a circuit is closed for energizing the signal controlling relay 1G from (+), through a circuit including front contact 322 of relay WP, polar contact 323 of relay WP in a left-hand normal position, front contact 324 of route relay 1—2R, winding of relay 1G, to (-).

The picking up of the contacts of the relay 1G changes the indication of the signal 1 from stop to clear so that a train may proceed over the route from signal 1 to signal 2 on to the end of such route. While the signal 1 is cleared, the locking relay L is deenergized in accordance with the usual practices for locking a route so as to prevent the operation of the switch machine during such a clearing condition of the route. Also, the passage of the train over the track section 14T, 40 deenergizes the track relay 14T opening front contact 318 so as to further insure the continued locking of the switch machine SM, although the signal is either automatically or manually put to stop.

In this connection, it is to be understood that the signal 1 may be entirely under manual control as shown in the present disclosure, or it may be a semi-automatic signal, that is, a signal automatically put to stop by the passage of a train. 50 It is also to be understood that this signal 1 and the other signals of the disclosure may be of the stick signal type, that is, put to stop by the passage of a train, and incapable of being cleared until both a stop and a clear control has again been received. This may be accomplished in any of the usual ways provided in signalling practice. But for the purpose of simplicity in the present disclosure, manual control only is provided for putting the signals to stop.

More specifically, the signal 1 is returned to its stop condition by the transmission over the system of the stop code in the response to the return of the route relay 1—2 to a deenergized condition, as previously pointed out.

This stop route code No. 13 sets up the code (-) (-) (+) (+) on the decoding relays PS and NS so that an execution circuit at the end of the cycle of operation is closed for the stop route relay 1—2S from (+), through a circuit including 70 back contact 300 of relay SA¹, front contact 301 of relay LV¹, back contact 325 of relay 4PS, back contact 326 of relay 5PS, back contact 327 of relay 6NS, back contact 305 of relay 7NS, front contact 328 of relay 4NS, front contact 329 of re- 75

lay 5NS, front contact 330 of relay 6PS, front contact 331 of relay 7PS, wire 332, windings of stop route relay 1-2S, to (-).

The stop route relay 1-2S, and also all other stop route relays, such as relay 4-6S, are only energized during the execution period, but this period of energization is sufficient for picking the stop route relay up and it remains up for a sufficient period of time to drop out any of the route relays with which it is associated. For example, the stop route relay 1-2S controls the route relay 1-2R and opens its stick circuit at back contact 312 and allows this route relay 1-2R to drop away putting to stop the signal by deenergizing relay 1G upon the opening of front contact 324.

It will be apparent from the above description that the transmission of any of the other route control codes as assigned in the typical code table 20 will cause the picking up of the corresponding route control relay and cause the setting up of the proper route and the clearing of its signal. Therefore, the remaining execution circuits for the route relays will not be pointed out in detail. 25 However, it is considered well to note that the picking up of the route relay 4-2R for example, closes front contact 333 which will energize the lower winding of the relay WR through an obvious circuit. The picking up of the relay WR 30 opens contact 316 to deenergize the stick circuit for the relay WN and closes its own stick circuit from (+), through a circuit including front contact 316, back contact 315 of relay WN, upper winding of relay WR, to (-). The closure of 35 front contact 320 of relay WR and back contact 321 of relay WN causes the reverse operating circuit of the switch machine SM, which will cause the crossover TS to operate to a reverse position which is repeated by the switch position repeating relay WP.

The front contact 334 of route relay 4-2R causes the energization of the signal clearing relay 5G for changing the indication of signal 5 from clear to stop, but this energizing circuit for 45 the relay 5G requires the switch position repeating relay WP to indicate that the crossover TS is in a reverse position before this circuit can be energized.

In brief, it will then be understood from this 50 operation, that each route control code not only causes the operation of the switch (or switches) in the associated route and the clearing of the signal for that route, but requires that the track switch (or switches) controlled thereby shall be 55 in proper positions and have responded to their controls properly before a signal can be cleared for that route. There is a route relay such as 1-2R, 2-1R, 4-6R, etc. for each of the routes. Also, each route may include a single track switch 60 or a plurality of track switches and crossovers although the present disclosure of Fig. 7 merely shows a single crossover. In such cases where a plurality of track switches are employed, the particular route relay picked up controls all of 65 the WN or WR relays for all of the track switches involved in the route which that route relay governs and the signal selecting circuits for controlling the signal relays G require that all of the track switches be in their proper operated positions before the proper relay G can respond to the energized condition of the route relay for that route.

Reception of emergency switch control code.— 70 As above described, and with reference to the 75 typical code table, it will be seen that code Nos.

7 and 8 are employed for the emergency operation of the switch machine SM in response to the manual control of the emergency switch control lever SML.

Let us assume that the reverse switch operating code No. 7 is transmitted and stored in the decoding relays PS and NS. This will set up an executing circuit at the end of the cycle from (+), through a circuit including back contact 300 of relay SA¹, front contact 301 of relay LV¹, back contact 302 of relay 4NS, back contact 326 of relay 5PS, back contact 304 of relay 6PS, back contact 305 of relay 7NS, front contact 335 of relay 4PS, front contact 336 of relay 5NS, front contact 337 of relay 6NS, front contact 338 of relay 1PS, wire 339, lower winding of relay WR, to (-). This circuit energizes the relay WR causing the relay WN to be deenergized and close the stick circuit for the relay WR previously pointed out. This will effect the operation of 20 the switch machine SM providing it is unlocked and no signal has been cleared. If the relay WN, for example, is energized by reason of the closed condition of front contact 314 of route relay 1-2R previously picked up for clearing a route, 25 then the relay WR will be only momentarily energized during the execution period and will again drop away as the relay WN is permanently held by the energization of its lower winding so long as the route relay 1-2R is picked up. It will be 30 apparent that the same condition exists if any other of the route relays were picked up requiring the crossover TS to be in a normal position.

Let us assume that the normal switch operating code No. 8 is transmitted and stored in the decoding relays PS and NS, this will set up an executing circuit at the end of the cycle from (+), through a circuit including back contact 300 of relay SA¹, front contact 301 of relay LV¹, back contact 302 of relay 4NS, back contact 326 of relay 5PS, back contact 304 of relay 6PS, back contact 340 of relay 7PS, front contact 341 of relay 4PS, front contact 342 of relay 5NS, front contact 343 of relay 6NS, front contact 344 of relay 7NS, wire 345, lower winding of relay WN, 45 to (-). This circuit energizes the relay WN causing the stick circuit for the relay WR to be broken and close its own stick circuit previously pointed out, providing of course that no route relay is holding the relay WR energized such as, 50 for example, the closed condition of front contact 333 of the route relay 4-2R. The control of the relay WN under such circumstances will be similar to that pointed out in connection with the relay WR.

Having thus described a centralized traffic controlling system of the entrance-exit interlocking type as one specific embodiment of the present invention, it is to be understood that various modifications, adaptations, and alterations may be applied to meet the requirements of practice without in any manner departing from the spirit or scope of the invention except as limited by the appended claims.

What I claim is:

1. In a centralized traffic controlling system for railroads, a track layout containing a plurality of track switches operable to normal and reverse positions to form a plurality of routes, signals for governing traffic over said routes, a code type communication system connecting a control office with said track layout, control buttons in said control office designating the ends of said routes through said track layout, means responsive to the joint operation of the control

- buttons for the opposite ends of any route for transmitting a distinctive code over said communication system, and means at the track layout responsive to each distinctive code for controlling all of the track switches to proper normal and/or reverse positions for the route selected by the operation of the two control buttons which caused the transmission of that code and for controlling its governing signal to a cleared condition after the operation of said switches in such selected route.
2. In a centralized traffic controlling system for railroads, a track layout containing a plurality of track switches to form a plurality of routes, signals for governing traffic over said routes, a code type communication system connecting a control office with said track layout, control buttons in said control office designating the ends of said routes through said track layout, means requiring the joint operation of the control buttons for the opposite ends of any particular route for transmitting a code over said communication system characteristic of that route, and means at the track layout responsive to each distinctive code for setting up the corresponding route by operating all of the track switches in that route and clearing its respective signal.
3. In a centralized traffic controlling system for railroads, a code type communication system connecting a control office and a distant track layout having a plurality of routes formed by the track switches included therein, a control button representing each route terminating point in the track layout, and means requiring the joint operation of a control button at each of the two terminating points for any particular route for transmitting over said communication system a code characteristic of that route.
4. In a centralized traffic controlling system for railroads, a code type communication system connecting a control office and a distant track layout having a plurality of routes formed by the track switches included therein, an initiating contact for the entrance point for each route, a completing contact for the exit point for each route, and means requiring the joint operation of an initiating contact and a completing contact for any particular route to cause the transmission of a code over said communication system characteristic of that route.
5. In a centralized traffic controlling system for railroads, a code type communication system connecting a control office and a distant track layout having a plurality of routes formed by the track switches included therein and having signals for governing traffic over the routes, manually governable means responsive if controlled to designate opposite ends of any given route for applying a code to said communication system characteristic of said given route, a route relay for each route through said track layout, said route relays being conditioned only upon the reception of their respective codes over said communication system, and circuit means controlled by each of said route relays for positioning the switches included in the route associated with that route relay and for clearing the signal governing such route only after all of the switches in the route have properly operated to positions required for that route.
6. In a centralized traffic controlling system for railroads, a code type communication system connecting a control office and a distant track layout having a plurality of routes formed by the track switches included therein, a control button representing each route terminating point in the track layout, and means responsive to the operation of the control buttons at the opposite ends of each route for transmitting a code over said communication system, which code is characteristic of only that route.
7. In a centralized traffic controlling system for railroads, a code type communication system connecting a control office and a distant track layout having both conflicting and nonconflicting routes, a control button for each route terminating point in the track layout, means responsive to the operation of the control buttons at the opposite ends of each route for transmitting a code characteristic of that route over said communication system, means allowing the transmission of the code for only one route from a group of conflicting routes, and means for causing the transmission in succession of the codes for nonconflicting routes when the control buttons identifying such routes are contemporaneously operated.
8. In a centralized traffic controlling system for railroads, a code type communication system connecting a control office and a distant track layout having a plurality of routes formed by the track switches included therein, a control button for each route terminating point in the track layout, and means controlled by and requiring only the joint operation of the two buttons identifying the terminating points of any particular route for controlling the track switches in that route, irrespective of their number, through the medium of said communication system.
9. In a centralized traffic controlling system for railroads, a code type communication system connecting a control office and a distant track layout having a plurality of routes formed by the track switches included therein, a control button for each route terminating point in the track layout, means controlled by the two buttons identifying the terminating points of any particular route for controlling the track switches in that route, irrespective of their number, through the medium of said communication system, and means for individually controlling each of said track switches through the medium of said communication system only when said control buttons are inactive with respect to those track switches to be controlled.
10. In a centralized traffic controlling system for railroads, a normally at rest code type communication system connecting a control office and a distant track layout having a plurality of routes formed by the track switches included therein, control buttons for the ends of said routes, route control means responsive to the joint operation of the control buttons for the opposite ends of any particular route for conditioning a code characteristic of that route, and means controlled by said route control means for initiating said system into operation, whereby said system is initiated when two cooperating control buttons have been actuated.
11. In a centralized traffic controlling system for railroads, a control office, a distant track layout having a plurality of routes formed by track switches, which routes have signals for governing traffic thereover, a code type communication system connecting said control office and said distant track layout, a control button for each route terminating point in the track layout, and means controlled by the actuation of two buttons alone for identifying the terminating points of

any particular route for controlling the track switches in that route and the signal governing traffic over that route, through the medium of said communication system.

- 5 12. In a centralized traffic controlling system for railroads, a multiple impulse type communication system connecting a control office and a distant track layout having a plurality of routes formed by the track switches included therein and 5
10 with signals for governing traffic thereover, control buttons for the ends of said routes, means responsive to the joint operation of the control buttons for the opposite ends of each route for transmitting distinctive control impulses over said 10
15 communication system, and means at said track layout responsive to said distinctive control impulses for controlling said track switches and signals to set up each of said routes.
13. In a centralized traffic controlling system 20 for railroads, a multiple impulse type communication system connecting a control office and a distant track layout having a plurality of routes formed by track switches with signals for governing traffic thereover, means at said distant track 20
25 layout appertaining to each route and responsive to a distinctive series of impulses characteristic of that route transmitted over said communication system for controlling said switches in that route and the clearing of the signal for one direction 25
30 over that route, manually operable control means for designating the entrance and exit ends of each route, and means responsive only to the joint operation of said manually operable control means to designate the entrance and exit ends 30
35 of a particular route for transmitting a distinctive series of impulses characteristic of that route over said communication system.

14. In a centralized traffic controlling system for railroads, a normally at rest code type communication system connecting a control office and a distant track layout having a plurality of routes formed by track switches, control buttons identifying the ends of said routes, and means responsive to the joint operation of the control 40
45 buttons for the opposite ends of a particular route for controlling all the track switches for that route through the medium of said communication system.

15. In a centralized traffic controlling system for railroads, a multiple impulse code type communication system connecting a control office and a plurality of field stations each including a track layout having a plurality of routes, manually operable control means in said control office 50
55 identifying the ends of said routes, and means responsive to the joint operation of said manually operable control means for the opposite ends of a particular route for transmitting a series of impulses over said communication system characteristic of that route and the field station at 55
60 which such route is located.

16. In combination, a track layout including track switches to form a plurality of routes, control buttons identifying the ends of said routes, 65
65 communication means of the code type responsive to the joint operation of the control buttons for the opposite ends of a particular route for controlling the switches in such route to establish that route when such communication means is 70
75 rendered effective, and a separate button capable when actuated of rendering said communication means effective for controlling the switches.

17. In a centralized traffic controlling system for railroads, normally at rest code type communication system connecting a control office 75

and a distant track layout having a plurality of routes formed by track switches, control buttons identifying the ends of said routes, route control means responsive to the joint operation of the control buttons for the opposite ends of a particular route for controlling all the track switches for that route through the medium of said communication system, manually operable individual control means for said track switches, switch control means responsive to the operation of said individual control means for operating said track switches through the medium of said communication system, and means interlocking said route control means and said switch control means so as to allow only one or the other to effect the control of said track switches at any one time. 15

18. In a centralized traffic controlling system for railroads, normally at rest code type communication system connecting a control office and a distant track layout having a plurality of routes 20 formed by track switches, control buttons identifying the ends of said routes, route control means responsive to the joint operation of the control buttons for the opposite ends of a particular route for controlling all the track switches for that 25 route through the medium of said communication system, manually operable individual control means for said track switches, switch control means responsive to the operation of said individual control means for operating said track 30 switches through the medium of said communication system, and interlocking means preventing said switch control means from interrupting the control of said track switches by said route control means. 35

19. In a centralized traffic controlling system for railroads, a multiple impulse type communication system connecting a control office and a distant track layout having a plurality of routes formed by track switches, control buttons for the 40 ends of said routes, individual control means for said track switches, route control means responsive to the joint operation of the control buttons for the opposite ends of such route for transmitting distinctive control impulses over said 45 communication system, switch control means responsive to the operation of said individual control means for transmitting distinctive control impulses over said communication system, and means at said track layout responsive to said 50 distinctive control impulses transmitted over said communication system for controlling said track switches, said means being arranged in such a manner that said impulses transmitted by said individual control means are ineffective while 55 said track switches are under the control of impulses transmitted by said route control means.

20. In a centralized traffic controlling system for railroads; a multiple impulse code type communication system connecting a control office 60 and a distant track layout having a plurality of routes formed by the track switches, some of which routes are conflicting and some of which are non-conflicting, said system being capable of transmitting only one code at a time, control 65 buttons for the ends of said routes; a bank of interlocked relays, only one of which can be picked up at any one time and each respectively identified with the said non-conflicting routes; means responsive to the joint operation of the control buttons for the opposite ends of each non-conflicting route for picking up its respective interlocked relay; means controlled by each interlocked relay for transmitting a distinctive code over said communication system character- 70
75

- istic of the non-conflicting route with which it is identified; and means at said track layout responsive to each said distinctive code for controlling said track switches and signals to set up 5 the corresponding route.
21. In a centralized traffic controlling system for railroads, a multiple impulse type communication system connecting a control office and a distant track layout having a plurality of routes 10 formed by track switches with signals for governing traffic thereover, control buttons in the control office for the ends of said routes, means responsive to the operation of the control buttons for the opposite ends of a particular route for 15 transmitting distinctive control impulses over said communication system, route control means at said track layout responsive to said distinctive control impulses transmitted over said communication system for identifying the ends of said 20 route, and means controlled by said route control means at the field station for controlling said track switches to proper positions to set up such route and for clearing the signals governing such route after it has been set up.
22. In a centralized traffic controlling system 25 for railroads, a stretch of railway track having a plurality of switches and signals for setting up different routes through the track layout, a plurality of field stations located adjacent the track layout and each having associated therewith certain ones of said switches and signals, a control office, a line circuit extending from the control office through the several field stations, manually operable control buttons for the 30 ends of said routes located on a control panel in the control office, means responsive to the joint operation of the control buttons for the opposite ends of each particular route for applying to said line circuit a distinctive combination of impulses 35 to form a code call characteristic of the station at which the switches and signals are located that are required to establish that particular route, said means also applying succeeding impulses corresponding to the controls for the switches and 40 signals at such field station, station selecting means at each of said stations selectively responsive to said distinctive combinations of impulses so as to select its station only when its code call 45 is impressed on said line circuit and when selected to render its station responsive to the succeeding impulses applied to said line circuit, and means at each station responsive to the succeeding control impulses to operate the 50 switches and signals for that station to establish 55 said particular route.
23. In a centralized traffic controlling system for railroads, a multiple impulse code type communication system connecting a control office and a plurality of field stations located along a 60 track layout including a plurality of switches and signals, a miniature track diagram located in said control office corresponding to said track layout, control buttons on said track diagram for each of the signal locations, code transmitting means responsive to the joint operation of the manually operable control buttons for two spaced signal locations for transmitting a code call over said communication system characteristic 65 of the station having apparatus for controlling the switches between said two spaced signals and thereafter transmitting code impulses for controlling such switches, and means at each field station selectively responsive to its code call to 70 render that station responsive to the succeeding 75 code impulses for controlling the switches located at that station.
24. In a centralized traffic controlling system for railroads, a multiple impulse type code communication system connecting a control office and a distant track layout having switches and signals, said communication system being capable of transmitting only a single code at any one time, a miniature track diagram in the control office corresponding to said track layout and having 10 manually operable control buttons located thereon at points corresponding to said signal locations, electro-responsive means controlled by the joint operation of the control buttons for two spaced signal locations for transmitting a code for controlling the switch or switches between such spaced signal locations and for clearing a particular one of said signals, and interlocking means including said electro-responsive means for allowing only one pair of control buttons to be effective 15 at the same time to transmit a code.
25. In a centralized traffic controlling system for railroads, a normally at rest multiple impulse type code communication system connecting a control office and a distant track layout having 20 switches and signals for governing traffic thereover, a miniature track diagram located in the control office corresponding to said track layout and having control buttons located thereon at points corresponding to said signals of the actual 25 track layout, and means responsive to and requiring the joint operation of the control buttons for two spaced signal locations for initiating and transmitting impulses over said code communication system to control the track switches between such signal locations and to clear a particular one of said two spaced signals.
26. In a centralized traffic controlling system for railroads, a code type communication system of the multiple impulse type connecting control 30 office and a distant track layout having a plurality of routes formed by the switches included therein, a control button for each route terminating point in the track layout, a manually operable switch control lever for each track switch in the track layout, each lever normally assuming an inactive position and operable to normal and reverse controlling positions, means controlled by the two buttons identifying the terminating 35 points of a particular route for transmitting control impulses over said communication system for controlling the track switches in that particular route, said means being effective to transmit a new control for a particular switch only providing the switch control lever for that switch is in an inactive position, and means controlled by each 40 switch control lever for transmitting control impulses over said communication system to control the corresponding track switch to a normal or reverse position as the case may be, said means 45 being effective to control a particular switch only when the corresponding track switch is not under the control of the control buttons at the opposite ends of any route in which such switch may be included.
27. In a centralized traffic controlling system for railroads, a normally at rest code type of communication system connecting a control office and a distant track layout having a plurality of routes formed by the track switches, a miniature 50 track diagram in the control office corresponding to said track layout and having control buttons identified with the ends of said routes, code transmitting means responsive to the joint operation of the control buttons for the opposite ends of a 55

- particular route for initiating said code communication system into operation to transmit control impulses to control the track switch or switches included in such route, a manually operable switch control lever for each of the track switches in the track layout, each of the said levers being normally inactive but operable to normal and reverse controlling positions, a manually operable starting button, transmitting means set into operation by the operation of said starting button and controlled by said switch control levers in normal or reverse positions for transmitting control impulses to operate the corresponding track switches to normal or reverse positions as the case may be, and means responsive to the different control impulses transmitted over said communication system for controlling said track switches, said means responding to said control impulses transmitted in accordance with said buttons for the opposite ends of a route irrespective of the control impulses last transmitted by said switch control levers.
28. In a centralized traffic controlling system for railroads, a multiple impulse type code communication system connecting a control office and a distant track layout having signals at spaced locations with intervening track switches for setting up different routes through said track layout, a miniature track diagram in said control office corresponding to said track layout, an entrance button on said track diagram for each of said signal locations, each of said entrance buttons being of the stay-where-put type, exit buttons on said miniature track diagram for each of said signal locations, each of said exit buttons being of the self-restoring type, and means responsive to the actuation of an entrance button to an operated position for the entrance point to a route and the momentary actuation of the exit button for the exit point to that route for transmitting control impulses over said code type communication system to control the track switches to proper positions to set up that route and to clear the signal at the entrance point of that route corresponding to the point for which the entrance button was operated, said means remaining effective so long as the entrance button remains in an actuated position irrespective of the self-restoration of the actuated exit button for that route, said means also being effective upon the restoration of the entrance button to a normal inactive position for transmitting control impulses to return said cleared signal to stop.
29. In a centralized traffic controlling system for railroads, a multiple impulse type code communication system connecting a control office and a distant track layout having a plurality of routes formed by the track switches and signals, some of which routes are conflicting and some of which are non-conflicting, said routes being divided into groups each of which includes a non-conflict-
- ing route and its associated conflicting routes, a control panel at said control office having control buttons for the ends of said routes, a bank of interlocked relays, only one of which can be picked up at any one time and each respectively identified with a particular one of said groups of routes, relay means responsive to the joint operation of the control buttons for the opposite ends of each particular route for picking up its respective interlocked relay for the group of routes within which such particular route is included, and means including said relay means and associated with the control buttons for the opposite ends of the routes within each particular group for preventing other than the control buttons for the opposite ends of only one of said routes to be effective at any one time to pick up its respective interlocked relay and to determine the control impulses transmitted over said communication system to control the track switches and signals to set up the corresponding route.
30. In a centralized traffic controlling system for railroads, a normally at rest multiple impulse code type communication system capable of transmitting control impulses from a control office to a distant field station during any cycle of operation when initiated into operation, a track layout at said field station having signals at spaced locations with intervening power-operated track switches for setting up different routes through said track layout, a miniature track diagram in said control office corresponding to said track layout, control buttons on said track diagram at points corresponding to the signal locations in the field, means responsive to the joint actuation of the control button for the signal location at the entrance to any given route and a control button for the exit end of that route to effect the initiation of said communication system into one cycle of operation for transmitting control impulses over said communication system to control the track switches to proper positions to set up the route designated by the operation of such buttons and to clear the signal at the entrance to that route, said means also being responsive to a different actuation of the control button for the signal location at the entrance to the route for initiating said communication system into another cycle of operation to transmit control impulses over said communication system to return the signal for the corresponding location to stop, and means at the field station responsive to the control impulses transmitted over said communication system during said one cycle of operation for controlling the track switches to set up that route and to clear the signal at the entrance to such route, said means also being responsive to said another cycle of operation for returning said signal to stop.
